UNITED STATES PATENT OFFICE

172,532

COMBINATION RAIN TRAP AND MUFFLER

Leino H. Billey, St. Paul, Minn., assignor to Donaldson Company, Inc., St. Paul, Minn., a corporation of Delaware

Application June 5, 1953, Serial No. 25,355

Term of patent 14 years

(Cl. D14—6)

To all whom it may concern:

Be it known that I, Leino H. Billey, a citizen of the United States, residing at St. Paul, county of Ramsey, and State of Minnesota, have invented a new, original, and ornamental Design for a Combination Rain Trap and Muffler, of which the following is a specification, reference being had to the accompanying drawing, forming a part thereof.

Fig. 1 is a view in top plan of a combination rain trap and muffler, showing my new design;

Fig. 2 is a view in side elevation; and
Fig. 3 is a view in bottom plan.

I claim:

The ornamental design for a combination rain trap and muffler, as shown.
